UNITED STATES PATENT OFFICE.

AAGE KARL JOHANNES BAUERS, OF COPENHAGEN, DENMARK.

KEYLESS LOCK SUITABLE FOR CYCLE LOCK AND THE LIKE.

1,408,434.

Specification of Letters Patent.

Patented Mar. 7, 1922.

Application filed October 25, 1919. Serial No. 333,268.

To all whom it may concern:

Be it known that I, AAGE KARL JOHANNES BAUERS, a subject of the King of Denmark, residing at No. 18 Bredgade, Copenhagen, 5 in the Kingdom of Denmark, have invented certain new and useful Improvements in Keyless Locks Suitable for Cycle Locks and the like; and I do hereby declare the following to be a full, clear, and exact 10 description of the invention, such as will enable others skilled in the art to which it appertains to make and use the same, reference being had to the accompanying drawings, and to letters or figures of reference marked 15 thereon, which form a part of this specification.

This invention refers to a keyless lock which, as desired, can be used as a stationary lock, padlock, or the like, and which, 20 among other uses, is also suitable as a cycle lock.

The lock consists of a movable member, which will here be called a bolt, and a number of latching-members which will here be 25 called tumblers. The bolt can be moved by means of a suitable outside member,—a knob, or the like and the tumblers have exterior extensions the ends of which form a kind of key-board. Each tumbler will, only 30 in a single, definite position, permit the bolt to be moved in the opening direction, while, in all other possible positions, it will catch and lock the bolt. Thus the condition for the opening of the lock is that all the tumblers assume the first mentioned position, 35 or the "free position". Between the bolt and the various tumblers, there is, by means of suitable members, accomplished such a co-operation that the tumblers, or some of 40 them are compulsively moved away from the "free position" when the lock is shut. All the exterior prolongations of the tumblers will then assume suitable uniformly situated positions (normal positions) so that it 45 is impossible to see on the key-board which tumblers are not to be moved, and which are to be moved, and in which direction they are to be moved. Considering the great number of possible combinations, it is 50 practically impossible for the lock to be opened by one who is unacquainted with the right combination, which can be varied indefinitely in the different individual locks,

even if the number of locks manufactured is very great. 55

One form of construction is, by way of example, diagrammatically shown in the drawing, where—

Figs. 1 and 2 are front views of the lock open and shut respectively, the front plates 60 of the case and bolt being removed;

Fig. 3 is a longitudinal section through the closed lock, part of the tumbler extensions being broken away;

Fig. 4 is a detail; and 65

Figs. 5-7 are three tumblers in free position (removed from the lock).

Fig. 8 is a detail plan view of the bolt.

The shown lock has an oblong case consisting of two plates 8 united by means of a 70 number of rivets 9. The bolt 10, which can be pushed up and down in the lock-case, consists of two plates, each plate formed with two narrow end pieces 10' extending transversely across the lock case, which end pieces 75 are connected by a wide central web 10" extending longitudinally of the lock case, the webs of the two plates being connected by means of a rectangular cross-piece 11. The shank 13 of a knob 12 is passed from 80 the front (to the right in Fig. 3) through the cross-piece 11 in which it is held by a nut 14 on the rear side and a spring 15 on the front. In the front plate of the lock-case there is a straight slit 16 for the shank 85 13, and in the rear plate there is a slit of the shape shown in Fig. 4, the upper part 17 of which has approximately the same shape as the nut 14, and whose lower part 18 has a similar but longer shape, while the 90 central part 19 only has the same width as the shank 13. The significance of these details will be more clearly set forth in the following.

On the middle rivets 9 of the lock-case 95 there are revolubly disposed arms 20, having pins 21 which engage in recesses 22 formed in suitable locking-members 23, which are revoluble around the lowermost rivets 9, but are only partly shown. They may e. g. be 100 claw-shaped members, which can grasp down around a wheel tyre and in between the wheel-spokes. The mutually facing sides of the arms 20 have projections 24 so that, when the cross-piece 11 is moved upward from the position shown in Fig. 2,

said projections lie in the path of the cross-piece and are therefore turned so that the arms finally brought into the position shown in Fig. 1, with the inner sides of these projections 24 in contact with the sides of the cross-piece. When the cross-piece is pushed down from this position it will meet other projections 25 on the arms 20, so that these arms are now turned opposite to their former direction and finally press against the sides of the cross-piece with the inner sides of the projections 25 (see Fig. 2).

At the first movement, the locking-members 23 are turned in such a direction that they are opened, and at the second movement they are shut.

The tumblers 26 are revolvably disposed on the top rivets 9, e. g. four on each. Their projections 27, which lie outside of the lock-case, form the aforesaid keyboard,—here in the form of two rows of keys 28.

In normal position (Figs. 1 and 2) these keys lie four in a row. In each tumbler there is a recess into which engage pins 29 on the bolt 10. Each of these recesses has approximately the shape of a spade, the lower part of whose "blade" has tapering edges 30, and whose "handle" 31 is either straight and proceeds from the centre of the upper edge 32 of the "blade" (Fig. 6) or is crooked and proceeds from one corner or the other of the "blade" (Figs. 5 and 7).

In order that the bolt may be moved from the position shown in Fig. 2 to that shown in Fig. 1, all the tumblers must assume positions such as those shown in Figs. 5-7, namely with the "handle" 31 of the recess situated just opposite the pin 29. If some, or only one, of the tumblers do not fulfill this condition, but have the edge 32 situated above the pin 29 (see right side in Fig. 1,) the opening of the lock is prevented.

When the normal position of the tumblers is such as that shown in Figs. 1 and 2, the "free" position and the normal position will coincide with respect to tumblers whose recess has the shape shown in Fig. 6. Thus such tumblers do not act obstructively in normal position, but obstruct when, if an attempt is made to open the lock, they are turned to the right or left. Tumblers such as those shown in Figs. 5 and 7 obstruct in normal position, and their keys must be turned to right and to left, respectively, in order to give a "free" position.

For instance, if three tumblers in the left row and two in the right row have the shape shown in Fig. 6, while one tumbler to the left and one to the right have the shape shown in Fig. 5 and one to the right has the shape shown in Fig. 7, it is necessary, in order to be able to push the bolt up, to turn just these certain tumblers,—all three of them and only them,—namely the keys

of the first two to the right and the key 65 of the last to the left.

When the bolt is pushed up, the three turned tumblers will, owing to the crooked shape of the "handles" 31, again be turned back into normal position.

When the bolt is again pushed down, the three tumblers, in the course of this movement, will first be turned out into "free" position and then, when the pin 29 engages one or the other of the oblique edges 30, will 75 be carried back to normal position.

The downward movement of the bolt takes place against a spring 33 which, e. g. is inserted between the upper part of the lock-case and the cross-piece 11. Thus this spring 80 tends to hold the lock-members 23 in opening position. A further assurance against unintentional closing of the locking members is attained by the co-operation between the nut 14 and the special slit 17, 19, 18 (Fig. 4). 85 When the lock is open, the nut 14, actuated by the spring 15, will be held in the widened top-part 17 of the slit, and the bolt 10, the arm 20, and the locking members 23 can be moved only when, by an inward pressure 90 on the knob 12, the nut 14 has been pushed out of the slit. An accidental push on the knob 12 will not destroy the security, even if the nut 14 is forced out of the slit, as the spring 33 will still hold the bolt up, and 95 the spring 15 will again pull the nut back into place.

If the lock is to be closed, one should first press in the knob 12, so as to loosen the nut 14, and then push the knob downward. Its 100 shank 13 will then slide in the central part 19 of the slit. When this central part is passed, the nut 14 springs into the widened lower part 18 of the slit and stops the sliding movement when its lower edge touches 105 the lower edge of the lower part 18 of the slit. The pins 29 will then be in the lowest corner of the tumbler recesses (see, in Fig. 2, the dotted lines indicating the positions 129 of the pins 29 and the position 111 of the 110 cross-piece 11), and all the tumblers will then assume normal position.

When the knob 12 is next let loose, the spring 33 will pull the bolt up until the nut 14 assumes the position shown in Fig. 4 and 115 stops the bolt.

The pins 29 are then in the broad part of the tumbler-recesses, so that the tumblers can now be turned.

When the lock is to be opened, it is first 120 necessary to release the nut 14 from the slit-section 18 by pressing on the knob 12. The spring 33 will then accomplish the opening movement, and finally the spring 15 will force the nut 14 into the top slit-section 17.

Each tumbler can only be turned through a certain angle, namely, until the pin 29 touches one side or the other of the recess.

The tumbler or tumblers that should be turned in order to be brought into "free" position shall each time be turned just this angle. Thus when the tumbler stops of its own accord, it is in "free" position. Therefore it is possible for the person who is acquainted with the lock to actuate the keyboard correctly by a single, quick grip.

I claim:—

- 10 1. A keyless lock comprising a casing, a locking member therein, a plurality of securing members pivotally mounted in the casing and having recesses therein, each recess terminating in a narrow slot and having 15 obstructing edges adjacent the slot, and pins on the locking members projecting into the recesses and cooperating with the latter to

control the movements of the securing members.

2. A keyless lock comprising a casing, a 20 bolt slidably mounted therein, a plurality of tumblers pivotally mounted in the casing and having extensions projecting outside the latter, pins on the bolt projecting into recesses formed in the tumblers, said recesses 25 having oblique end edges for engaging the pins whereby the tumblers are moved into normal position, a spring, and a stopping device cooperating with the latter to hold the locking mechanism in open position. 30

In testimony that I claim the foregoing as my invention, I have signed my name.

AAGE KARL JOHANNES BAUERS.
